CLAIM

The ornamental design for an outrigger for trolley, as shown and described.

DESCRIPTION

FIG. 1 is a perspective view of a first embodiment of an outrigger for trolley showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is a perspective view of the design in a use status;
FIG. 10 is a perspective view of a second embodiment of an outrigger for trolley;
FIG. 11 is another perspective view thereof;
FIG. 12 is a front view thereof;
FIG. 13 is a rear view thereof;
FIG. 14 is a left side view thereof;
FIG. 15 is a right side view thereof;
FIG. 16 is a top plan view thereof;
FIG. 17 is a bottom plan view thereof; and,
FIG. 18 is a perspective view of the design in a use status. The broken lines in the figures show environment and form no part of the claimed design.
